UNITED STATES PATENT OFFICE

147,632

DESIGN FOR A MOTOR VEHICLE CAB

Charles S. Ash, Milford, Mich.

Application December 29, 1945, Serial No. 125,196

Term of patent 7 years

(Cl. D14—3)

To all whom it may concern:

Be it known that I, Charles S. Ash, a citizen of the United States of America, residing in Milford, in the county of Oakland and State of Michigan, have invented a new, original, and ornamental Design for a Motor Vehicle Cab, of which the following is a specification, reference being had to the accompanying drawings, forming a part thereof.

Figures 2, 3 and 4 are a front elevational view, a top plan view and a side elevational view, respectively, of the motor vehicle cab shown in Figure 1.

The rear of the motor vehicle cab is a plain flat surface except for the conventional rear window partly shown in Fig. 1.

The other side of the motor vehicle cab is the same as that illustrated.

The dotted line showing in the several drawing figures is for illustrative purposes only.

I claim:

The ornamental design for a motor vehicle cab, as shown and described.

CHARLES S. ASH.
